US0D1111011S

(12) **United States Design Patent** (10) **Patent No.:** **US D1,111,011 S**
(45) **Date of Patent:** **** Feb. 3, 2026**

(54) **SMART WATCH**

(71) Applicant: **Shenzhen Starmax Technology Co., Ltd.**, Shenzhen (CN)

(72) Inventor: **Zhongtao Han**, Guangdong (CN)

(73) Assignee: **Shenzhen Starmax Technology Co., Ltd.**, Shenzhen (CN)

(**) Term: **15 Years**

(21) Appl. No.: **29/895,250**

(22) Filed: **Jun. 20, 2023**

(30) **Foreign Application Priority Data**

Feb. 14, 2023 (CN) 202330048780.7

(57) **CLAIM**

The ornamental design for a smart watch as shown and described.

DESCRIPTION

FIG. 1 is a front, right and top perspective view of the first embodiment of a smart watch, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front, right and top perspective view of the second embodiment of the smart watch.

FIG. 10 is a rear, left and bottom perspective view thereof.

FIG. 11 is a front elevation view thereof.

FIG. 12 is a rear elevation view thereof.

FIG. 13 is a left side elevation view thereof.

FIG. 14 is a right side elevation view thereof.

FIG. 15 is a top plan view thereof; and,

FIG. 16 is a bottom plan view thereof.

The broken lines depict portions of the smart watch that form no part of the claimed design.

1 Claim, 16 Drawing Sheets
